UNITED STATES PATENT OFFICE.

MARCEL PERREUR-LLOYD, OF LONDON, ENGLAND, ASSIGNOR TO THE ELECTRICAL COPPER COMPANY, LIMITED, OF SAME PLACE.

ELECTRODEPOSITING-CELL.

SPECIFICATION forming part of Letters Patent No. 636,212, dated October 31, 1899.

Application filed December 28, 1897. Serial No. 663,833. (No model.)

To all whom it may concern:

Be it known that I, MARCEL PERREUR-LLOYD, a citizen of the French Republic, residing at London, in the county of Middlesex, 5 England, have invented new and useful Improvements in Electrodepositing-Cells, (for which I have obtained patents in Great Britain, Nos. 2,709, 2,710, 2,711, and 2,712, bearing date the 2d day of February, 1897,) of which 10 the following is a specification.

This invention relates to apparatus for the electrodeposition of copper and other metals upon rotary cathodes wherein an organic membranous substance is used in contact 15 with the cathode for the purpose of insuring a dense homogeneous deposit.

According to this invention the organic membranous substances which are known as and are called herein "impregnators" consist of animal membranes—such as skins, intestines, and bladders—which have had removed from them any adherent or excessive fatty or fleshy matters and which have preferably been subjected for a few hours to the 25 action of a lime-bath. The membranous substances which are at present employed are such as are naturally or artificially charged with fatty or adhesive insulating matters which coat any projection from the surface 30 of the rotary cathode practically in the same manner as the faces of type are coated in rotary typography. This coating with an adhesive insulator is only temporary and is removed by the combined actions of the electrolyte and of the impregnators. As hereinbefore stated, I, on the contrary, am careful to deprive the membranous substances which I employ as my impregnators of all excess of fatty and fleshy matters in practically the same way 35 40 and to the same extent as sheep and calf skins are similarly deprived in the manufacture of parchment and vellum. If my impregnators so prepared are microscopically examined, it will be found that they consist of a tangled 45 mass of minute fibers and filaments, which are chiefly composed of fibrin, gelatin, and albumen. If they are plunged in water at or below a temperature of about 60° Farenheit, these fibers and filaments remain unaltered 50 and their mass is found to be, while unaltered in construction, soft and yielding to the touch.

I may employ the impregnators in this condition, or I may further treat them to render them more insoluble in the event of the temperature of the bath accidentally rising above 55 60° Farenheit, as, owing to the density of the electric current and the resistance of the electrolyte, it may do in warm weather. For this purpose the membranous substance may be immersed for a short time in a bath containing 60 from two and one-half to five per cent. of potassium bichromate in water and be thereafter solarized or exposed to light and washed, as in certain photographic processes. Other methods may be employed for rendering the 65 impregnators more insoluble in a similar manner, as is well understood. In use the impregnators are simply arranged in light contact upon the surface of the cathode, so that the least roughness or asperity thereon seizes 70 some of the minute fibers and filaments, with which it becomes so covered as to prevent or retard the further deposition of metal thereon. In the meantime the deposition proceeds upon the surface surrounding the asperities, and 75 the former will thus become relatively higher and higher, while the fibers are removed by the wash of the electrolyte and the contact of the impregnators. As the relative heights of the asperities diminish they will take up or 80 be covered by fewer and fewer of the fibers until finally, with the equality in height with the surrounding surfaces, no more fibers are seized and the last of them are washed off or removed, whereupon the deposition becomes 85 again uniform.

It has been found that when organic impregnators are used, as hereinbefore described, and particularly when they have not been treated with a view to render them more insoluble, it 90 is necessary to maintain the bath in the working vat at a temperature which should not exceed 60° Farenheit. If this temperature should be exceeded, a solvent action on the impregnators results, which not only wastes 95 them, but fouls the electrolyte. To avoid this result, I adopt precautions to insure that the bath is kept sufficiently cool. This may be accomplished by a system of circulation and cooling which may be accompanied by 100 the insufflation of air and filtration. The insufflation of air not only oxidizes any organic

matter in the bath, but tends also to precipitate any iron there may be in solution. The oxidation may be aided by the addition of oxidizing agents. It is also then necessary to 5 provide means for getting rid of any of the organic matter which may come into solution or suspension.

Having now particularly described and ascertained the nature of my said invention and 10 in what manner the same is to be performed, I declare that what I claim is—

1. In an electrodepositing-cell, the combination with an anode and a rotary cathode, of a normal animal skin or membrane arranged 15 in light contact with the rotary cathode and

freed from all matters which can become soluble or adhesive at or below 60° Fahrenheit.

2. In an electrodepositing-cell, the combination of an anode, a rotary cathode, and an impregnator arranged in light contact with 20 the rotary cathode, said impregnator being composed of normal animal skins or membranes freed from excess of fatty matters and from matters which are or can become soluble or adhesive at or below 60° Fahrenheit.

MARCEL PERREUR-LLOYD.
